PHOTOGRAPHIC FLASH METER

Clarence Lee Folden, Downers Grove, Ill., assignor to Sears, Roebuck and Co., Chicago, Ill., a corporation of New York

Application May 7, 1956, Serial No. 41,390

Term of patent 14 years

(Cl. D61—1)

FIG. 1

FIG. 4

Fig. 1 is a perspective view of a photographic flash meter embodying my design,

Fig. 2 is a side elevation of the same, showing the side not visible in Fig. 1.

Fig. 3 is a rear elevation thereof, and
Fig. 4 is a bottom view of the same.

I claim:

The ornamental design for a photographic flash meter, as shown.
